(57) **CLAIM**

The ornamental design for a package for linens, as shown and described.

DESCRIPTION

FIG. 1 is a front view of the package for linens showing the new design.

FIG. 2 is a front perspective view of the package for linens of FIG. 1.

FIG. 3 is a top view of the package for linens of FIG. 1.

FIG. 4 is a bottom view of the package for linens of FIG. 1.

FIG. 5 is a left-side view of the package for linens of FIG. 1.

FIG. 6 is a right-side view of the package for linens of FIG. 1.

FIG. 7 is back view of the package for linens of FIG. 1.

FIG. 8 is a front view of the package for linens of FIG. 1 shown in an exemplary display environment with other packages arranged up side down in a stacked configuration;

FIG. 9 is a front view of the package for linens of FIG. 1 shown in an exemplary display environment with other packages arranged right side up in a stacked configuration;

FIG. 10 is a front view of the package for linens of FIG. 1 shown in an exemplary display environment with other packages arranged up side down in a stacked configuration upon shelving;

FIG. 11 is a front view of the package for linens of FIG. 1 shown in an exemplary display environment with other packages arranged right side up in a stacked configuration upon shelving;

FIG. 12 is a back view of the package for linens of FIG. 1 shown in an exemplary display environment with every other packages arranged up side down in a stacked configuration;

FIG. 13 is a back view of the package for linens of FIG. 1 shown in an exemplary display environment with other packages arranged right side up in a stacked configuration;

FIG. 14 is a back view of the package for linens of FIG. 1 shown in an exemplary display environment with every other packages arranged up side down in a stacked configuration upon shelving; and,

FIG. 15 is a back view of the package for linens of FIG. 1 shown in an exemplary display environment with other packages arranged right side up in a stacked configuration upon shelving.

The broken lines in the drawings represent unclaimed environmental subject matter.
